BUFFING AND POLISHING WHEEL

Nathan C. Hunt, Salem, Ohio

Application May 19, 1934, Serial No. 726,555

15 Claims. (CL. 51—194)

The invention relates to high-speed rotary buffing and polishing wheels having a flexible abrasive band detachably mounted on the periphery of the wheel.

More particularly, the invention relates to polishing wheels having means for taking up the slack in the detachable abrasive band, and for imposing a tensioning force thereon to keep the band tight on the wheel and to compensate for stretching which may occur in the band.

Certain prior buffing and polishing wheel constructions have included means for tensioning the abrasive band upon the wheel, but in such constructions, when the wheel is rotated at high speeds the centrifugal force acting upon the tensioning means may cause the tensioning pressure on the band to be diminished.

Certain other prior buffing and polishing wheel constructions have provided tensioning means for the abrasive band, which means are adapted to be actuated by the centrifugal force of the wheel when rotated, so that the amount of tension imparted to the abrasive band varies in proportion to the speed of rotation, and with the position or leverage of the tensioning weight. However, in these latter prior constructions, as the rotating band becomes stretched due to various conditions such as wear, heat or centrifugal force, the tensioning means necessarily changes its position radially to compensate for the stretch of the band, with the result that the wheel becomes unbalanced, statically and/or dynamically.

In all prior constructions of which I am aware, it is attempted to statically and possibly, dynamically balance the wheel, but no successful provision has been made for automatically maintaining static and dynamic wheel balance as the band becomes partially or permanently stretched, and for automatically maintaining static and dynamic wheel balance at varying speeds, within practical operating limits.

Obviously, a wheel which is statically balanced is not necessarily dynamically balanced, because the dynamic balance depends, not only upon the mass of the parts, but also upon their location.

In order to be efficient in continuous operation at high speeds, it is imperative that a polishing wheel be possessed of a high degree of strength for mechanical safety, be delicately and accurately balanced dynamically and statically, and be adapted for maintaining a smooth uniform buffing surface in continuous operation.

It is therefore an object of the present invention to provide a polishing wheel having tensioning means for maintaining an abrasive band

tight on the periphery of the wheel at all speeds.

Another object is to provide a polishing wheel having tensioning means for automatically dynamically and statically balancing the wheel when the same is rotated.

A further object is to provide tensioning means mounting the abrasive band on the wheel for quick detachment therefrom.

Another object is to provide tensioning means for automatically taking up stretch occurring in the abrasive band while the wheel is rotating and simultaneously maintaining the dynamic and/or static balance of the wheel.

Another object is to provide improved means for securely anchoring the ends of the abrasive band to the wheel without causing tearing of the band when the same is under tension.

A further object is to provide improved anchoring means for the ends of the band, which means will grip the band with increased force as the tension in the band increases.

A still further object is to provide an improved clip for anchoring the end of an abrasive band, which clip can be easily applied to a range of bands of various thicknesses.

Other objects include the provision of a simply and compactly designed polishing wheel having a high degree of strength, and which is adapted for maintaining a smooth uniform buffing or polishing surface at the most efficient peripheral speeds in continuous operation.

These and other objects are attained by the improvements comprising the present invention, which may be stated in general terms as including a wheel frame having a drum flange, a cushion for the drum flange, the drum flange and cushion being slotted for receiving the ends of a buffing or abrasive band wrapped around the periphery of the cushion, means for rigidly securing or anchoring one end of the band in the frame, and means for applying a yielding tensioning force to the other end of the band, the component parts of said tensioning means acting radially of the wheel in such manner as to automatically, statically and/or dynamically balance the same.

A preferred embodiment of the present invention is shown in the accompanying drawings in which

Figure 1 is a plan sectional view of the improved polishing wheel, taken substantially on line 1—1, Fig. 4, and showing the abrasive band loosely wrapped around the same before tension is applied;

Similar numerals refer to similar parts throughout the drawings.

The improved polishing wheel is indicated generally at 10, and preferably includes two similar frame members 11 and 11', clamped together in abutting relation as by bolts indicated at 12 passing through bosses 13 and 13' provided on the respective frame members.

The frame members 11 and 11' preferably include side disk portions 14 and 14' and peripheral drum flanges 15 and 15' respectively. Thus the abutting frame members 11 and 11' form a closed drum, and the abutting flanges 15 and 15' form the facing surface upon which the abrasive cushion 16 is mounted.

The cushion 16 may be of rubber, or may comprise a cork base with a rubber or fabric facing, or with a composite rubber and fabric facing, or with a leather facing. The cushion or its component parts may be vulcanized, cemented or otherwise secured to the facing surface provided by the drum flanges 15 and 15'.

As shown in Figs. 1, 2, 3 and 11, the drum flanges and the cushion are slotted at 17 transversely of and throughout the width of the drum for receiving the ends of a flexible abrasive loop or band 18 which is wrapped around the outer periphery of the cushion 16.

The improved polishing wheel 10 may be quickly attached to or detached from any rotatable spindle. Preferably, the frame members 11 and 11' are provided with hub portions 19 and 19' respectively for receiving a spindle 20.

Means for securing the wheel 10 upon spindles having slight variations in diameter preferably includes a ring 21 fitted in each of the hub portions 19 and 19' at the side disks 14 and 14' respectively, and each ring 21 has a tapered or

conical inner surface as shown at 22 in Fig. 4.

An annular clamping collet 23 is located within each ring 21, and has a tapered outer surface 24 conforming to and abutting the inner surface 22 of the ring, and an inner cylindrical surface 24a 5 for fitting around the spindle 20. The annular portion of each collet 23 is slotted radially at intervals as shown at 25. The outer face of one of the collets 23 abuts a shoulder 26 on the spindle 20, and the outer face of the other collet abuts 10 a thrust washer 27. Preferably, a nut 28 is screwed on the outer end of the spindle 20 for abutting the washer 27.

By adjusting the nut 28, the collets 23 may be wedge-fitted between the rings 24 and the spindle 15 20, so as to secure the buffing wheel 10 upon spindles having slight variations in diameter. Moreover, collets 23 with other sized bores may be used for mounting a particular size of wheel on shafts of other diameters from that shown. 20

The frame members 11 and 11' are preferably provided with abutting webs indicated generally at 30 and extending radially from the hub portions 19 and 19' to the drum flanges 15 and 15'. The webs 30 include outer web portions 31 extending radially inward from the drum flanges, and inner web portions 32 extending radially outward from the hub portions.

The outer web portions 31 are slotted transversely throughout the width of the wheel as shown at 33 and the slot 33 registers with the slot 17 in the drum flanges and the cushion, and extends radially inward from slot 17 to the inner end portions of the outer web portions 31. At their abutting surfaces and preferably axial with the slot 33, the webs 31 are provided with a cylindrical bore 34 extending radially inward from the slot 17 to the hub portions 19 and 19'.

Preferably, at the intersection of the drum flanges 15 and 15' and the webs 30, the frame members 11 and 11' are provided with abutting band anchoring webs 35. A transversely extending clip holding member 36 preferably made of spring steel is fitted in said webs and has a length substantially equal to the width of the wheel. 45

The ends of the abrasive band 18 have secured thereon metal clips 37, in a manner to be described, and one of said clips is inserted endwise in the clip holding member 36, as best shown in Fig. 11, the webs 35 being slotted at 38 to receive 50 the adjacent end portion of the abrasive band 18. Thus one end of the abrasive band is securely held in the band-holding webs 35 of the frame members.

The other clip end of the band is inserted endwise in a clip holding member 36' similar to member 36, and the member 36' is substantially coextensive with the width of the band 18 and is located in the slot 33.

As best shown in Figs. 11 to 16 inclusive, improved means are provided for anchoring one end of the abrasive band to the wheel frame and for securing the other end to the tensioning means.

The band 18 is preferably made of paper, fibre, fabric or cloth and the like, and has abrasive grains imbedded in one surface. Prior means for gripping or anchoring the ends of the band have been found to puncture or cut the fabric, etc., and/or crush the abrasive grains thereon so as to 65 cause the band to rupture or tear under tension.

The improved clip 37 is substantially U-shaped in cross section, and the legs 37a have rounded ends; and as shown in Fig. 12, the legs of the clip when formed are spaced apart slightly more than 75

the maximum thickness of the abrasive band to be gripped.

The clip is made of relatively strong and soft metal such as aluminum, or of strong and soft 5 other material. The inner surfaces of the legs 37a are preferably provided with a series of serrations indicated at 37b.

One end of the band 18 is inserted into the clip 37 and the legs 37a are then squeezed together 10 sufficiently to grip the band tightly, as shown in Fig. 13. The soft metal serrations are adapted to press into the surface of the fabric of the band without puncturing the same. On the abrasive 15 surface of the band, the serrations force themselves against and in between the grains and the grains become imbedded in the clip material so as to prevent withdrawal of the band unless the legs of the clip are spread apart.

When the ends of the band 18 with the clips 37 20 squeezed thereon are inserted endwise in the clip holding members 36 and 36', and tension is applied to the band, the rounded ends of the legs 37a abut the plane surfaces of the angular flange portions 39 of the holder, and the band extends 25 through a slot 36a provided between the flange portions 39. This slot is slightly wider than the maximum thickness of band to be used.

The flange portions 39 are disposed to the sides of the holding members 36 and 36' at an 30 angle so calculated as to abut and tend to compress the ends of the legs 37a together when tension is applied to the band, and increasingly grip the band more tightly as the tension is increased.

The improved clip and clip holding member are 35 adapted to anchor the ends of bands of varying thicknesses less than the relative thickness of the band shown in Figs. 13 and 14.

As shown in Figs. 15 and 16 the improved clip 40 may be applied to a very thin band indicated at 118.

The legs 37a of the clip are squeezed together sufficiently to tightly grip the band 118, and the clip 37 assumes the shape shown in Figs. 15 and 16. The overall thickness of the clip and band 45 is greater than the width of the slot 136a in the holder 136', so that the rounded ends of the legs are abutted and compressed together by the plane surfaces of the angular flange portions 139, when the band is under tension.

50 A tension link 40 is slidably mounted in the bore 34, and its upper or outer end is bifurcated to form ears 41 which are pivotally secured to the sides of the clip holding member 36' at its longitudinally central portion by pins 42, as best shown in Fig. 11. Thus the end of the abrasive band 18 is pivotally connected at its laterally central portion to tension link 40, so that tension applied to said link will be equally distributed over the width of the band and the direction of the pull of the band on the link is coaxial with the link.

55 Preferably, the upper or outer portion of the bore 34 is enlarged as shown at 34a to accommodate the heads of pins 42. A washer 34b of cork and the like, is preferably located in the web portions 31 below the enlarged portion 34a of the bore, for closely fitting around link 40 and sealing the portion 34a from bore 34.

A cross bar 44 extends transversely through the lower or inner end of link 40 preferably in the 70 plane of the abutting surfaces of the frame members. The inner web portions 32 are slotted as at 45 in the plane of their abutting surfaces for slidably receiving the cross bar 44, and the slot 45 extends radially from the hub portions 19 and 19' 75 to the outer web portions 31.

The improved tensioning means preferably includes cylinders 50 mounted one on each side of the webs 30, and preferably secured to side disk 14 by means of screws 51 screwed in bosses 52 provided on the side disk 14 (Fig. 9).

5

The axes of the cylinders 50 are preferably in the plane of the abutting surfaces of the frame members 11 and 11', that is, in the median plane laterally of the wheel. The axes of the cylinders 50 are located at a particular acute angle with 10 the axis of bore 34 and link 40, for a purpose to be hereinafter described.

Each cylinder 50 is provided at its inner end with an inturned spring retaining flange 53. A spring abutting disk 54 is slidably mounted in 15 each cylinder, and a coil compression spring 55 is interposed between the flange 53 and the disk 54.

An airplane strand cable 56a of substantially 20 nonexpansible material connects one of the disks 54 with one end of the cross bar 44, and a similar 20 cable 56b connects the other disk 54 with the other end of the cross bar 44 for transmitting the compressive force of springs 55 to the link 40 to cause an inward pull on the end of the abrasive band 18 to which the link 40 is connected. 25

Each of the cables 56a and 56b is preferably 30 double and is looped over one end of the cross bar 44 to fit in a groove provided therein, as shown.

The two strands of each of the cables 56a and 56b are led inward from cross bar 44 in a direction parallel to the bore 34 and link 40, and pass successively around a pair of pulleys 57 and 58, mounted on pins 59 and 60 which are journaled in bosses 61 and 62 respectively, provided on the 35 side disks 14 and 14' (Fig. 6).

From the pulleys 58, the two strands of each of the cables 56a and 56b pass into one of the respective cylinders 50, and the ends of the strands are connected with the respective disk 54 of the cylinder. Between the pulleys 58 and the disks 40 54, the strands of the cable are preferably parallel with the axis of the respective cylinder 50.

As shown in Fig. 10, the ends of each cable 56a or 45 56b are secured to one of the disks 54 by passing the cable strands through diametrically opposite portions of a boss 63 provided on the central portion of disk 54, and thence led into grooves provided on the underside of a clamping plate 64 which is secured to the disk 54 by means of a 50 screw 65 screwed into the disk 54.

Thus the pull or tensioning force imparted to the abrasive band 18 by the compression of springs 55, through cables 56a and 56b, cross bar 44 and link 40, is transmitted in directions substantially radially of the wheel; that is, the force 55 components of the tensioning means act radially of the wheel.

Means for manually moving the link 40 radially outward against the compression of springs 55, and for holding said link in its outermost position 60 to permit connection of the clip end of band 18 in the clip holding member 36', preferably includes a lever member 68 pivotally mounted on the side disks 14 and 14' of the frame members 11 and 11' by means of a pin 69 journaled in bosses 70 65 provided on said frame members adjacent the drum flanges 15 and 15'.

A longitudinally slotted plate 71 is pivotally connected at its upper end to the end of arm 70 68a of lever member 68, as at 72, and the strands of the cable 56a pass through the slot 73 (Fig. 6) of the plate 71.

The lower end of plate 71 is provided with a transverse portion 74, which is located between 75

the cable 56a and the web 30. By rotating the lever member 68 in a counter-clockwise direction about its pivot 69, the transverse portion 74 may be engaged in a notch 75 provided in the bar 44, for moving the link 40 radially outward.

Means for manually rotating the lever member 68 may include a shaft 76 journalled in bosses 77 provided on the side disk members 14 and 14'. As best shown in Fig. 5, the shaft 76 extends throughout the width of the wheel 10 and is provided at its ends with squared sockets 78 for receiving a suitable wrench.

At its central portion, the shaft 76 is provided with a slot 76a adapted to receive arm 68a of lever 68, and crank arms 79 extend angularly from shaft 76 adjacent slot 76a for journalling a roller 80 on pivot pin 81. The roller 80 is adapted to engage a spring steel plate 68b secured to the underside of the arm 68a. Rotation of the shaft 20 76 in a counter-clockwise direction will move the lever member 68 from the position shown in Figs. 2 and 3 to the position shown in Fig. 1, with the transverse portion 74 of the plate 71 engaging the notch 75 in cross bar 44, to move the link 40 to 25 its outermost position, as shown in Fig. 1.

In this position, the roller 80 has been moved over center with respect to the shaft 76 so that the link 40 will be held in its outermost position until shaft 76 is initially rotated in a clockwise 30 direction by means of a wrench.

Also, in this position the roller 80 engages the curved portion 82 of the spring steel plate 68b, which curved portion acts as a stop to limit movement of the roller 80 in a counter-clockwise 35 direction.

Preferably, the lever member 68 is provided with an arm 83, which may be weighted as indicated at 83a, so that when the wheel is in operation the moment of the arm due to centrifugal 40 force will hold it out against the drum flange 15 and 15', as shown in dot-dash lines in Fig. 1, and maintain the means for moving link 40 radially outward in the positions shown in Figs. 2 and 3.

Weighted bosses 84 and 85 are provided on 45 frame members 11 and 11' respectively at locations substantially opposite the webs 30, for partially maintaining the static balance of the wheel, or in other words for bringing the center of gravity 50 of the wheel at its geometric center.

In applying an abrasive band 18 to the improved 55 wheel 10, the link 40 is first moved radially outward to its outermost position by inserting a wrench in one of the sockets 78 of the shaft 76 and rotating the same counter-clockwise to the position shown in Fig. 1, in a manner previously described.

One clip end 37 of the abrasive band 18 is then 60 inserted endwise into the clip holding member 36 and the band wrapped around the outer periphery of the cushion 16 to bring the other end of said band into the slot 17. The free clip end 37 of the band is then inserted endwise into the clip holding member 36' which is pivotally attached to the link 40, and the band assumes a 65 position substantially as shown in Fig. 1.

The shaft 76 is then rotated in a clockwise direction to bring the roller 80 over center, at which time the compressive force of the springs 55 moves the disks radially outward and the disks 70 act through cables 56a and 56b to pull the link 40 radially inward to the position shown in Fig. 2 and impose a tensioning force or pull upon the band 18, bringing it tightly into contact with the cushion 16 throughout its length. At the same 75

time the lever member 68 moves toward the position shown in Fig. 2.

As viewed in Figs. 1 and 2, the radial inward movement of link 40 and the inward movement of members 68 and 71 causes the center of gravity 5 of the wheel to be shifted slightly downwardly. The acute angles between the axes of cylinders 50 and the link 40 are so calculated that as the disks 54 are moved radially outward by the springs to pull the link 40 radially inward, the center of 10 gravity of each disk and spring assembly is shifted radially outward and upward with respect to the center of the wheel a sufficient distance to compensate for the downward movement of the center of gravity of the wheel and return the same 15 to the geometrical center of the wheel.

Thus the wheel is automatically statically balanced regardless of variations in the length of the abrasive band 18 between limits determined by the radial length of slot 45, such as may result 20 from permanent stretch in the band due to continued wear, because as the band becomes longer, the springs move the link 40 inward which causes the center of gravity of the wheel to shift accordingly, but this shift is compensated for by the corresponding radially outward movement of the disks 54 and springs 55, so that the parts may assume the positions indicated in dot-dash lines in 25 Fig. 3.

Assuming the parts to be in the positions of Fig. 30 2, when the wheel is rotated at high speeds, the centrifugal force acting on the abrasive loop or band 18 is compensated for or balanced by the centrifugal force acting on the springs 55 and disks 54 so that the band is kept tightly against 35 the cushion 16. The centrifugal force overcomes the force tending to extend the compression springs 55 and moves them away from the flanges 53, further compressing the springs, as shown in Fig. 3, so that at high speeds the tensioning pull 40 on the band is entirely provided by the centrifugal force on the springs 55 and disks 54 acting radially of the wheel.

By means of this construction, the band is 45 maintained tight on the cushion 16 so as to maintain a smooth, uniform buffing or polishing surface, and the wheel is automatically maintained in dynamic and/or static balance at high speeds.

I claim:

1. A polishing wheel having a drum face, a 50 cushion secured on the drum face, an abrasive band surrounding said cushion, and means on the wheel for always imposing a tension on the abrasive band and for automatically statically balancing the wheel for varying amounts of tension. 55

2. A polishing wheel having a drum face, a cushion secured on the drum face, an abrasive band surrounding said cushion, and means on the wheel for always imposing a tension on the abrasive band as the length thereof is varied between 60 predetermined limits and for automatically statically balancing the wheel for varying lengths of the band.

3. A polishing wheel having a drum face, a cushion secured on the drum face; an abrasive band surrounding said cushion, means on the wheel for always imposing a tensioning pull on the abrasive band for maintaining the band tight on the cushion and for maintaining the dynamic 65 balance of the wheel as the wheel is rotated at high speed.

4. A polishing wheel having a drum face, a cushion secured on the drum face, an abrasive band surrounding said cushion, means on the 70 75

wheel for imposing a tensioning pull on the abrasive band, said tensioning means being acted upon by centrifugal force to increase the tensioning pull on the band and to maintain the dynamic balance of the wheel as the wheel is rotated at high speed.

5. A polishing wheel having a drum face, a cushion secured on the drum face, an abrasive band surrounding said cushion, means on the wheel for imposing a tensioning pull on the abrasive band, said tensioning pull being automatically increased in exact proportion to the increase in tension in the band as the speed of rotation of the wheel is increased.

10. 6. A polishing wheel having a drum face, a cushion secured on the drum face, an abrasive loop surrounding said cushion, means for detachably securing one end of the loop to the wheel, link means movable radially of the wheel, means for detachably connecting said link means to the other end of the loop, and yielding means movable radially of the wheel for imparting a tensioning pull to said link means in a direction parallel to its path of movement.

15. 7. A polishing wheel having a drum face, a cushion secured on the drum face, an abrasive loop surrounding said cushion, means for detachably securing one end of the loop to the wheel, link means movable radially of the wheel, means for detachably connecting said link means to the other end of the loop, yielding means movable radially of the wheel for imparting a tensioning pull to said link means in a direction parallel to its path of movement, and manually operable means for moving said link means outward and for maintaining said link means at its outermost position.

20. 8. A polishing wheel having a drum face, a cushion secured on the drum face, an abrasive loop surrounding said cushion, means for detachably securing one end of the loop to the wheel, link means movable radially of the wheel, means for detachably and pivotally connecting said link means to the other end of the loop at its laterally central portion, and yielding means movable radially of the wheel for imparting a tensioning pull to said link means.

25. 9. A polishing wheel having a drum face, a cushion secured on the drum face, an abrasive loop surrounding said cushion, means for detachably securing one end of the loop to the wheel, link means movable radially of the wheel, means for detachably connecting said link means to the other end of the loop, and yielding means acting radially of the wheel at an acute angle with the path of movement of the link means for imparting a tensioning pull to said link means.

30. 10. A polishing wheel having a drum face, a cushion secured on the drum face, an abrasive loop surrounding said cushion, means for detachably securing one end of the loop to the wheel, link means movable radially of the wheel, means for detachably connecting said link means to the other end of the loop, yielding means movable radially of the wheel at an acute angle with the path of movement of the link means, and flexible substantially non-stretchable means connecting

the link means to the yielding means, component parts of said flexible means moving substantially radially of the wheel.

35. 11. A polishing wheel having a drum face, a cushion secured on the drum face, an abrasive loop surrounding said cushion, means for detachably securing one end of the loop to the wheel, and means for applying a yielding tensioning pull to the other end of the loop, component parts of said tensioning means acting radially of the wheel in angular relation to each other so as to automatically statically balance the wheel.

40. 12. A polishing wheel having a drum face, a cushion secured on the drum face, an abrasive loop surrounding said cushion, means for detachably securing one end of the loop to the wheel, and means for applying a yielding tensioning pull to the other end of the loop, component parts of said tensioning means acting radially of the wheel in angular relation to each other so as to automatically dynamically balance the wheel.

45. 13. A polishing wheel having a drum face, a cushion secured on the drum face, an abrasive loop surrounding said cushion, means for detachably securing one end of the loop to the wheel, clip means secured on the other end of said loop, link means movable radially of the wheel, and yielding means for imparting a tensioning pull to said link means, said clip means being pivotally connected at the central portion laterally of the loop to said link means for exerting a pull on the link means in a direction coaxial therewith.

50. 14. In a polishing wheel having an abrasive band, means for anchoring an end of the band to the wheel including a substantially U-shaped clip having serrated inner surfaces for gripping the band, the free ends of the legs of the clip being rounded, and means surrounding the clip provided with a slot through which the end of the band extends having plane surfaces engaged by said rounded clip ends extending from each side of the slot and angularly converging toward said band end, whereby when tension is applied to the band, the plane surfaces react against said rounded clip ends to automatically compress and wedge the free ends of the clip toward each other and increasingly grip the band end more tightly as the band tension is increased.

55. 15. In a polishing wheel having an abrasive band, means for anchoring an end of the band to the wheel including a substantially U-shaped clip having serrated inner surfaces for gripping the band, the free ends of the legs of the clip being rounded, and a clip holder surrounding said clip provided with a slot through which the end of the band extends and having angular flange portions provided with plane surfaces engaged by said rounded clip ends extending from each side of the slot and angularly converging toward said band end, whereby when tension is applied to the band, the plane surfaces of the holder react against said rounded clip ends to automatically compress and wedge the free ends of the clip toward each other and increasingly grip the band end more tightly as the band tension is increased.

NATHAN C. HUNT.
